UNITED STATES PATENT OFFICE.

ARTHUR WILLIAMS, OF GRAND RAPIDS, MICHIGAN, ASSIGNOR TO WILMARSH & MOR-
MAN COMPANY, OF GRAND RAPIDS, MICHIGAN, A CORPORATION OF MICHIGAN.

MICROMETER ADJUSTMENT FOR WORKTABLES OF GRINDING MACHINES.

Application filed August 23, 1924. Serial No. 733,688.

This invention relates to a novel construction of micrometer adjustment for work tables of metal working machines. In practice, I have applied this invention to the work tables of grinding machines though the invention is not to be considered as limited in use to this one type of machine.

It is a primary object and purpose of the present invention to apply to the work carrying table mounted to swing about a vertical axis on and above a sub-table, a means for adjusting said work table to minute exactness and this in a very simple and effective manner. The invention consists of novel devices of constructions, combinations and arrangements of parts for practically and effectively attaining the above named object, as will fully appear when understanding of the invention is had from the following description, taken in connection with the accompanying drawings, in which,

Fig. 1 is a plan view, with parts broken away and shown in section, of an upper work table and a lower sub-table having my invention applied thereto.

Fig. 2 is a front elevation thereof.

Fig. 3 is a fragmentary plan of the sub-table at the middle portion thereof and showing the studs used to connect the upper table and sub-table in horizontal section.

Fig. 4 is a fragmentary vertical section through the structure, the section being on a broken plane passing through the rear attaching stud and one of the front attaching studs.

Fig. 5 is a like view, the section being so as to show the manually operable micrometer screw in side elevation, and

Fig. 6 is a perspective view of the arc-shaped member carried in the circular slot in the upper side of the sub-table and which is used in effecting the micrometer adjustment of the upper table with respect to the sub-table.

Like reference characters refer to like parts in the different views of the drawings.

The sub-table 1 may be of any desired construction, being elongated, and in grinding machines it may be mounted for reciprocatory movements in the direction of its length. This table substantially midway between its ends, is formed with an integral upwardly extending circular portion or boss

2 in which a circular T-slot 3 is cut, at one side having a lateral enlargement 3^a for the passage of the heads of T-bolts into the slot as shown in Fig. 3. A stud 4 is centrally located in the boss to serve as a pivot on which the upper or work carrying table may be mounted, said stud at its upper end having an enlarged head 4^a, as shown in Fig. 4. Within the slot 3 an arc-shaped member 5 is seated toward the front and one side of the slot (see Fig. 3) and in the upper side of the member 5 two notches 6 and 7 are cut part way through the member, the notch 6 being of less width than the notch 7.

The upper or work carrying table 8 is formed on its under side with a downwardly projecting circular boss 9 of substantially the same diameter as and adapted to rest upon the boss 2, previously described, there being a recess centrally located in the under side of said boss 9 for reception of the enlarged head 4^a of the stud 4. It will be noted that the vertical grooved outer surface of the boss 2 carries a graduated scale and that the boss has a cooperating indicating mark or pointer which, as the upper boss 9 is turned about the axis of stud 4, moves to different positions with respect to the graduations of the scale so as to indicate the amount of angular adjustment. The boss 9 is also formed with an upwardly projecting portion 9^a having a flat upper surface through which attaching studs, later described, pass.

Cast integral with the upper table is a forwardly projecting barrel 10 internally bored as indicated at 11 for the passage of the micrometer screw, as will later appear. The boss 9 is also formed adjacent this barrel with a vertical oblong opening or slot 12 as shown. In the rear side of the table an under cut slot 13 is provided. Two studs 14 having heads 14^a received in the wider lower portions of the T-slot 3 extend upwardly through the boss 9, one into the slot 13 at the rear and the other at the left of the slot 12. These studs are threaded at their upper ends for the reception of nuts and it is evident that when the nuts are tightened the upper table is held fixed with respect to the sub-table. A third stud 15 has a head 15^a at its lower end received within the enlarged lower portion of the T-slot 3 and seats in the notch 7 of the member 5. This stud passes

upwardly through a bushing 16 which is located in and passes through the opening or slot 12 its upper edge extending a short distance above the upper surface of the part 9^a, 5 as best shown in Fig. 4.

A pin 17 depends from a head 18 and at its lower end is received within the notch 6 in member 5, head 18 being located in a recess cut in the upper table 8. Head 18 has an 10 opening bored through the same which is threaded for the reception of the inner threaded end of a micrometer screw 19 located lengthwise of the opening 11 and equipped at its outer end, beyond the end of 15 the barrel 10, with a small knurled hand wheel 20 whereby the screw may be manually operated. The part 19 is enlarged toward its outer end and has a continuous groove 21 cut around the same into which 20 the inner end of a screw 22 passing through a side of the barrel 10 is adapted to be received, this holding the micrometer screw 19 against any longitudinal movement.

When it is desired to change the position 25 of the upper table with respect to sub-table, the nuts on studs 14 and 15 are loosened and the upper table is moved approximately to its desired position. With this movement the heads 14^a and 15^a of the studs shift in 30 the slot 3 and of course the member 5 is moved and shifted with the movement of the stud 15. When the upper table has been moved to its approximate position the nut at the upper end of stud 15 is tightened this 35 locking the sleeve 16 securely against the sub-table and at the same time locking the member 5 against movement. The upper table however is then permitted a slight movement in either direction owing to the elongation of 40 the slot 12 through which the sleeve 16 passes. The micrometer screw is then turned in the desired direction and the pin 17 seating in the notch 6 of member 5 serves to hold the head 18 against movement whereupon turning 45 the micrometer screw rod 19 compels the movement of the upper table. This movement is very slight with each turn of the micrometer screw and it is evident that a very minute and exact adjustment may be had. When the upper table has reached its 50 desired position the nuts at the upper end of studs 14 are tightened and the upper table is then held in fixed position with respect to the sub-table.

The construction described is very practical, relatively simple to manufacture, and with it a very easy yet exact adjustment of the work carrying table with respect to the sub-table may be had. The device is operable from the front of the machine and is in a convenient place for access by the operator of the machine. In practice this construction has proved particularly satisfactory. The invention is defined in the appended claims and is to be considered as

comprehensive of all forms of structure coming within their scope.

I claim:

1. In combination with an elongated sub-table, an elongated work holding table located above and mounted on the sub-table to turn about a vertical axis located between the ends of said tables, said sub-table having a circular T-slot cut in the upper side thereof, T-bolts located in the slot and extending upwardly through the upper table said bolts being equipped with nuts for clamping the upper table to the sub-table, a manually operable member rotatably mounted on the upper table, and means interposed between said member and the sub-table and partly seated within the T-slot for adjusting the upper table to different degrees of angular adjustment with respect to the sub-table. 70

2. In combination, an elongated sub-table 85 provided between its ends with an upwardly projecting circular boss having a circular T-slot cut therein, an arc-shaped member seated in the slot, said member in its upper side having two notches cut therein, an upper work holding table pivotally mounted on the sub-table to turn about an axis coincident with the center of said boss, said upper table having a relatively short oblong slot cut therein above the T-slot in the sub-table, a stud having a head seated in the T-slot and extending upwardly through said oblong slot, a sleeve around the stud within the oblong slot and projecting a short distance above the adjacent upper side of the work holding table, additional studs having heads seated in the T-slot and extending upwardly through the work holding table, nuts threaded onto the upper ends of the studs, said stud passing through the sleeve having its head seated in one of the notches of the arc-shaped member, a head having a depending pin seated in the other notch of the arc-shaped member, said head having a threaded opening therethrough and a rotatably mounted screw threaded rod carried by the work holding table and passing through said head, said rod at its outer end being equipped with a hand wheel for manual operation, substantially as and for the purpose described. 90

3. In combination, an elongated sub-table, an elongated work holding table located above the sub-table and pivotally mounted thereon to turn about a vertical axis, means for releasably clamping the work holding table to the sub-table, said means when released permitting the work holding table to swing about said vertical axis, additional means movable with the work holding table and adapted to be operated to limit the angular movement of the work holding table to a limited extent, and means carried by the work holding table manually operable to turn the work holding table about its pivotal 110 120 125 130 135 axis.

axis minute amounts after said means has been operated to limit the turning movement of the work holding table.

4. In combination an elongated sub-table formed between its ends and in its upper side with a circular T-slot therein, an arc shaped member seated in the slot, its upper side having two spaced apart notches cut therein, an upper work holding table pivotally mounted on the sub-table to turn about a vertical axis coincident with the center of the slot, said upper table being formed with a relatively short oblong slot located above the T-slot in the sub-table, a stud having a head seated in the T-slot extending upwardly through said oblong slot, a sleeve around the stud within said oblong slot projecting a short distance above the upper side

of the work holding table, additional studs having heads seated in the T-slots extending upwardly through the work holding table, releasable means on the upper ends of said studs for clamping the work holding table to the sub-table, said stud which passes through the sleeve having its head seated in one of the notches of the arc shaped member, a pin formed with an upper head seated at its lower end in the other notch of the arc shaped member, said head having a threaded opening therethrough and a rotatably mounted screw threaded rod carried by the work holding table and passing through said head and adapted to be manually turned, substantially as described.

In testimony whereof I affix my signature.
ARTHUR WILLIAMS.
